UNITED STATES PATENT OFFICE.

SALVATORE SCOGNAMILLO, OF NEW YORK, N. Y.

SPARKING PLUG.

1,200,243.

Specification of Letters Patent. Patented Oct. 3, 1916.

Application filed June 28, 1915. Serial No. 36,791.

To all whom it may concern:

Be it known that I, SALVATORE SCOGNAMILLO, a citizen of the United States, residing at New York, in the county of New York and State of New York, have invented new and useful Improvements in Sparking Plugs, of which the following is a specification.

This invention relates to sparking plugs, 10 and one object of the same is to provide a device of this class having a compact arrangement and a comparatively small number of parts whereby the cost of manufacture and the market price may be materially 15 reduced without in the least detracting from the necessary efficiency of this class of devices.

A further object of the invention is to provide a sparking plug of materially reduced 20 vertical proportions and embodying electrode carrying means that may be readily placed and secured in position in a shell or plug member without requiring a particular adjustment or subsequent manipulation to properly dispose the electrode.

A still further object of the invention is to provide a sparking plug wherein the several parts are snugly assembled and all 30 spaces or openings between the side of the body wall and top portion of the plug and the carrier inserted in said body are entirely eliminated to avoid the presence of any air within the plug above the terminals of the electrodes and also to produce a watertight 35 inclosure for the conductor and the electrodes by forming the means for holding the conductor in flat disk-like form and applying thereto as a closure for the plug a vertically reduced screw-cap which flatly 40 bears on the said carrier, the cap filling the upper portion of the body or shell of the plug and obstructing the entrance or presence in the upper part of the plug of any moisture.

45 With these and other objects and advantages in view the invention consists in the preferred construction and arrangement of parts which will be more fully hereinafter described and claimed.

50 An embodiment of the invention is disclosed in the accompanying drawing, and in this drawing:—

55 Figure 1 is a transverse vertical section through a sparking plug embodying the features of the invention. Fig. 2 is a detail cross-sectional view of the electrode car-

rier and electrodes and showing the binding screw in elevation. Fig. 3 is a top plan view of the electrode carrier shown broken away and illustrating the conducting plug 60 for the electrodes in horizontal section. Fig. 4 is a section through the electrode carrier taken in the plane of the line 4—4, Fig. 2. Fig. 5 is a bottom plan view of the plug. Fig. 6 is a top plan view of the plug. 65

The numeral 5 designates the plug body or shell which is tubular or hollow and has a plurality of lower exterior screw-threads 6 for application of the plug in a threaded opening of an explosive engine or other device to which the plug may be connected. The upper part of the interior of the body or shell 5 has an annular shoulder 7 formed therein and provided with a seat 8 for a washer 9 of any suitable material, preferably asbestos. Immediately above the annular shoulder 7 the interior of the body or shell 5 is enlarged in diameter relatively to the lower portion of the said body, and the upper interior portion of the enlarged part of the body is formed with a plurality of screw-threads 10 to receive the threads 11 of a flat screw-cap 12. Between the lowermost thread of the series of threads 10 and the shoulder 7, the upper 80 interior portion of the body or shell is smooth to removably receive a carrier 13 which is of disk-like form and constructed of suitable insulating material, such as porcelain or bakelite. The carrier 13 has a 90 metallic conducting plug 14 inserted or molded therein, the said conducting plug having a screw-threaded opening 15 extending through the outer end thereof. The outer end of the conducting plug 14 is exposed through an opening 16 in the carrier, and engaging the screw-threaded opening or socket 15 is a binding screw 17, an insulating collar 18 being applied over the exposed portion of the screw and held 95 against the outer end of the conducting plug 14.

The electrodes 19 and 20 are secured in the carrier and the conducting plug by boring the latter, said electrodes being separated as required and depending from the carrier. The carrier as a whole embodies the disk-like body of insulating material, the conducting plug 14 and the electrodes 19 and 20 and may be termed an electrode carrier which is inserted in the top portion of the body or shell 5 and bears on the 100 105 110 115

washer 9 and adjacent portion of the shoulder 8. When the electrode carrier is mounted in the body or shell 5 the screw-threaded socket or opening 15 of the conducting plug 14 is disposed in alinement with an opening 21 in the side of the body or shell, and into this opening the screw-threaded shank or stem 15 and the collar 18 forming part of the binding screw are inserted, as clearly shown by Fig. 1. The electrodes 19 and 20 depend through the interior of the lower portion of the body or shell 5 and straddle a cross or transversely extending contact 22 secured to the lower portion of the body or shell and forming the ground connection, as it were, which will be readily understood. The conducting plug or conductor 14 may be round or circular in cross-section, or flat as may be desired, and it will be observed that when the carrier 13 is placed within the body or shell 5 it will simultaneously dispose the electrodes 19 and 20 in working position for the reason that the said electrodes will be guided in a proper direction to straddle the electrode 22, and when all of the electrodes are so arranged or as illustrated by Fig. 1 the screw socket in the conductor plug will be open to or in alinement with the opening 21 of the body or shell 5. When the screw cap 12 is inserted in the upper end of the body or shell it will firmly bear upon the upper surface of the carrier and tightly force the latter downwardly against the annular shoulder 7 and washer 9, the washer preventing any leakage between the shoulder and the lower portion of the carrier bearing thereon. The insulating collar 18 will also obviate any tendency to sparking between the outer end of the conductor 14 and the head of the screw 17, and by this means sparking will always be forced to take place between the electrodes 19 and 20 and 22.

From the foregoing it will be seen that the parts of the improved sparking plug are compact and may be readily assembled. There is no liability of short-circuits between the conductor and the insulating carrier, and air gaps or spaces as well as moisture collecting spaces are entirely obviated by the construction hereinbefore specified. Moreover, the cost of manufacture of the several parts is materially reduced in view of their simplicity and facility in assembling the same.

What is claimed is:

1. In a sparking plug, a body having an interior annular shoulder in the upper portion thereof and a side opening at a point slightly above the shoulder, a carrier consisting of a flat body formed of insulating material and of disk-like contour, said body having a metallic conductor fully inclosed therein and exposed solely at one extremity

through the said body and provided with a screw-threaded socket opening through the said exposed extremity thereof, the conductor also having a pair of separated electrodes extending from the lower portion upwardly therethrough and through the conductor and terminating at the top of the latter, the electrodes equally depending below the bottom of the carrier, the body having a lower cross conductor disposed between the free ends of the said electrodes, a screw cap fitted in the upper portion of the body and bearing directly on the top surface of and fully covering the upper portion of the body of the carrier and operating to hold the latter tightly against the shoulder of the body, and a binding post having a screw-stem inserted in the side opening of the body and the screw socket of the conductor.

2. A sparking plug having a body, a conductor in the lower portion thereof, a flat carrier of insulating material held in snug engagement with the plug in which it is disposed to obviate formation of air and water spaces within the plug and provided with a metallic conductor fully inclosed therein in diametric relation thereto, the carrier shielding all parts of the conductor from exposure to any part of the body adjacent thereto, electrodes in engagement with the conductor and extending only partially through the carrier and depending below the latter, a flat screw cap directly engaging and fully covering the top portion of the carrier and closing the upper part of the plug and thereby wholly inclosing the carrier in the plug, the projection of the cap at the upper portion of the plug being minimized to reduce the vertical extent of the plug as a whole, and a binding screw inserted through the upper portion of the side of the plug and engaging the conductor in the carrier and in part insulated from the said carrier and the body of the plug.

3. An electrode carrier for a sparking plug consisting of a flat disk-like body formed of insulating material and having a metallic conductor inserted and wholly inclosed therein and normally exposed solely at one end within the periphery of the disk-like body of the carrier, the flat disk-like body interposing an insulation between the whole conductor and all parts of the device to which the carrier may be applied, the conductor being provided with a screw socket extending partially therethrough and opening outwardly through the normally exposed end of the said conductor, the conductor being also provided with a pair of electrodes having their upper ends held in spaced relation and terminating in the conductor, said electrodes depending below the disk-like body, and a binding screw for engagement with the screw socket exposed at

one end of the conductor and having an insulating sleeve to close the normally exposed end of the conductor within the periphery of the carrier.

- 5 4. An electrode carrier for a sparking plug consisting of a flat circular disk formed of insulating material and having a diametric opening extending only partially therethrough, the carrier being of such dimensions as to snugly fit within the inclosure to which it is adapted to be applied, a metallic conductor or plug inserted in the said opening of the disk and wholly inclosed within the latter, said conductor being normally exposed only at one end within the periphery of the disk, a pair of electrodes inserted through the conductor at an angle to and terminating in the latter and depending below the bottom of the disk, and a binding screw removably engaging the conductor at the exposed end of the latter and provided with insulating means to close over the normally exposed end of the conductor.
- 10 5. A sparking plug having a body with

an inner annular shoulder, an electrode carrier consisting of a flat insulating disk disposed on said shoulder and provided with a metallic conductor wholly inclosed by and extending diametrically thereinto and having a pair of electrodes terminating and secured therein and depending below the disk, a binding screw extending through the side of the body into the metallic conductor, and a flat screw cap movably engaging the upper end of the body and bearing directly upon and holding the electrode carrier in place and fully inclosing the said carrier in the body, the body also having a conducting means disposed between the free ends of the electrodes.

In testimony whereof I have hereunto set my hand in presence of two subscribing witnesses.

SALVATORE SCOGNAMILLO.
